UNITED STATES PATENT OFFICE.

EDWARD F. NIEDECKEN, OF MILWAUKEE, WISCONSIN, ASSIGNOR TO HOFFMAN & BILLINGS MANUFACTURING COMPANY, OF MILWAUKEE, WISCONSIN, A CORPORATION OF WISCONSIN.

WASTE MECHANISM.

Application filed May 5, 1920. Serial No. 378,995.

To all whom it may concern:

Be it known that I, EDWARD F. NIEDECKEN, a citizen of the United States, residing at Milwaukee, in the county of Milwaukee and State of Wisconsin, have invented certain new and useful Improvements in Waste Mechanism, of which the following is a specification, reference being had to the accompanying drawing, forming a part thereof.

This invention relates to waste mechanism for bath tubs and similar receptacles and the object of the invention is to improve the construction and operation of waste mechanism in the manner to be hereinafter described and claimed.

Referring to the drawings which accompany this specification and form a part hereof, which drawings illustrate an embodiment of this invention, and on which drawings the same reference characters are used to designate the same parts in each of the views, Fig. 1 is a vertical section of the waste mechanism, parts being shown in elevation; and Fig. 2 is a vertical section taken on the line 2—2 on Fig. 1, looking in the direction indicated by the arrows.

Referring to the drawings, the reference numeral 1 designates a bath tub, or liquid receptacle, which is provided with an outlet aperture 2 and an overflow aperture 3. A pipe connection 4, which is provided with a flange 5, is screwed into the elbow 6 and a packing 7 makes a fluid tight joint. The elbow 6 is connected with the stand pipe 8 in line with a tubular valve 9. The valve 9 has an upper, circumferential valve face 10 and a lower, circumferential valve face 11. The upper valve face 10 projects beyond the body of the valve and the lower valve face 11 is arranged within the circumference of the body of the valve so that the valve may be readily assembled or disassembled. Inwardly projecting valve seats 12 and 13 are provided for the valve faces 10 and 11. It will be readily seen from an inspection of Fig. 1 of the drawings that, with this construction, when the valve 9 is closed, fluid cannot escape from the receptacle 1 either up or down past the valve 9 while fluid overflowing is free to pass through the valve 9. The valve body 14 is preferably provided with a guide or steady flange or rib 15 which is located opposite the elbow 6 to guard

against displacement or binding of the valve 9 when the valve is partly opened and fluid is running to waste through the elbow 6. The tubular body 16 of the valve 9 makes a substantially close fit within the valve seat 12 to prevent fluid from rising past the valve 9 and fouling the interior of the stand pipe 8 and the parts at the lower end thereof. This construction makes the mechanism sanitary and reliable. The valve seat 12 serves as a scraper to remove deposits on the exterior of the valve 9 and, as it is very short vertically, there is no opportunity for soap, for example, to work in between the valve and the seat and produce corrosion, sticking and wear.

The valve 9 can be raised and lowered in any suitable manner. The drawings illustrate a knob 17 connected with the valve and studs 18 and 19 projecting into inclined grooves in a member at the top of the stand pipe so that the valve can be opened and closed and can be held open in a common and well-known manner.

One of the difficulties heretofore encountered in installing bath tub wastes has been due to the different inclinations of the ends of bath tubs in which the overflow apertures were located. I overcome the difficulty by using an overflow pipe 20 which projects into a nipple 21 on the stand pipe 8 and which is made smaller than the interior of the nipple so that it can be turned out of direct line with the nipple. A packing 22 makes a fluid tight joint and the follower 23 is bored larger than the pipe 20. The pipe 20 is provided with a flange 24 to seat against the bath tub, and the joint is made tight by a packing 25. A rod 26 is screw-threaded at both ends and is screwed into a nut 27, passes through the grating 28 and is provided with a nut 29 on its end bearing against the grating. The nut 27 is movable within the nipple 21 so that the rod 26 can assume different angles. The drawings illustrate the nut 27 as pivoted on pivot screws 30 and 31, which are screwed into the nipple 21 and engage with recesses in the nut 27.

The advantages of the invention are of great importance from practical and sanitary standpoints. One standard overflow fitting can be properly and effectively secured to bath tubs, or receptacles, the in-

clinations of the ends of which vary. The foul waste water does not reach the interior of the stand pipe and befoul the same, and all of the surfaces exposed to the foul waste fluid are in direct line with the flow of the fluid to be flushed by the flow of the fluid.

The valve body 14 is provided with the waste inlet 32 and the stand pipe 8 is provided with the overflow inlet 33 above the waste inlet 32. The stand pipe 8 and the waste pipes 34 and 35 are illustrated by the drawings as connected with the valve body 14 by means of slip joint connections to illustrate a practical and convenient method of making pipe connections.

What I claim is:

1. In a waste mechanism, the combination with a valve body provided with a waste inlet and inwardly projecting valve seats above and below the waste inlet, of a tubular

valve provided with upper and lower valve faces to coat with said valve seats.

2. In waste mechanism, the combination with a valve body provided with a waste inlet, inwardly projecting valve seats above and below the waste inlet and a guide opposite the waste inlet, of a tubular valve provided with upper and lower valve faces and a body to be positioned by said guide. 30

3. In waste mechanism, the combination with a valve body provided with a waste inlet and inwardly projecting valve seats above and below the waste inlet, of a tubular valve provided with upper and lower valve faces to coat with said valve seats and also provided with a body part, the upper valve seat closely fitting the body part of the valve. 35

In witness whereof I hereto affix my signature.

EDWARD F. NIEDECKEN.
